UNITED STATES PATENT OFFICE

146,350

DESIGN FOR A JEWELRY PIN

Kathryn M. Dunn, Hammond, Ind.

Application April 24, 1946, Serial No. 128,917

Term of patent 14 years

(Cl. D45—19)

To all whom it may concern:

Be it known that I, Kathryn M. Dunn, a citizen of the United States, residing at Hammond, in the county of Lake and State of Indiana, have invented a new, original, and ornamental Design for a Jewelry Pin, of which the following is a specification, reference being had to the accompanying drawing, forming part thereof.

Figure 1 is a plan view of a jewelry pin, showing my new design;

Figure 2 is a left end view; and

Figure 3 is a right end view.

I claim:

The ornamental design for a jewelry pin, as shown.

KATHRYN M. DUNN.
